UNITED STATES PATENT OFFICE.

JOHN H. DERBY, OF NEW YORK, N. Y.

SIGNAL TRANSMITTER.

Application filed June 17, 1922. Serial No. 569,069.

To all whom it may concern:

Be it known that I, JOHN H. DERBY, a citizen of the United States, residing at New York city, N. Y., have invented certain new and useful Improvements in Signal Transmitters, of which the following is a clear, full, and exact description.

This invention relates to transmitter boxes such as are used in connection with fire alarm and other signal transmitting systems, and has for its general object to improve the construction of such boxes with respect to the simplicity and the durability of the mechanism, and also with respect to certainty of operation and automatic supervision. The invention aims particularly to devise a transmitter box and an associated signal system which has especial utility in hotels, hospitals and other places where it is desirable to have means for transmitting either a silent alarm or a general alarm including a warning signal to the people in the building.

Important features of the invention are the provision in a transmitter box supervised by a normally closed circuit including a trip magnet in said box of means associated with the armature of said magnet for insuring the separation of the armature from the magnet when the operating current is cut down so that only the supervising current is left in the circuit; the provision of means for automatically supervising a normally open code signal circuit; the provision of means for automatically indicating when the box is run down, and the provision in the box of resistance which may be short-circuited to cause the operation by the break wheel of a normally open but automatically supervised floor circuit.

Other objects and important features of the invention will appear from the following description and claims when considered in connection with the accompanying drawings, in which—

Figure 1 is a front elevation of a transmitter box embodying the invention, with the cover removed;

Fig. 2 is a plan view of the transmitter mechanism, the box being shown in section;

Fig. 3 is a section on the line 3—3 of Fig. 1;

Fig. 4 is a detail view showing the pawl

and ratchet for retaining the driving spring in wound condition;

Fig. 5 is a perspective detail of the contacts or switch members associated with the means for operating the box by hand and for testing the operation of the box without transmitting a signal;

Fig. 6 is a detail view showing the escapement associated with the make-and-break train of mechanism;

Fig. 7 is a sectional view showing the resistance contained in the box and the means for short-circuiting this resistance;

Fig. 8 shows the box tripping mechanism in its normal retaining position;

Fig. 9 shows the tripping mechanism in its tripping position;

Fig. 10 is a perspective detail of the armature and its associated releasing spring;

Fig. 11 is a view, one-half scale, of the inner face of the box cover;

Fig. 12 is a wiring diagram of the box and the associated control board, and

Fig. 13 is a wiring diagram of the trouble circuits constituting a part of the automatic means for supervising the box and its connected signal system.

The illustrated transmitter box comprises an enclosing casing, which is shown as a cylindrical box 2, of bronze, iron or other suitable material, having a cover plate 4 which is removable to permit inspection of the mechanism of the box, only a small part of the mechanism of the box being carried by the cover plate.

The train of mechanism through which the make-and-break signal transmitting means of the box is operated is carried by a frame comprising front and rear plates 6 and 8 suitably spaced by posts 10, the plate 8 being attached to the rear wall of the casing or box 2. The train of mechanism comprises a segment gear 12 rigidly attached to the drum portion 14 (see Fig. 3) of the spring shaft 16, the drum portion 14 of this shaft having attached thereto a driving spring 18, the outer end of which is connected to one of the posts 10. It will be noted that the drum portion 14 of the shaft 16 has shoulders abutting the plates 6 and 8 whereby it also helps to maintain these plates properly spaced.

The segment gear 12 meshes with a pin-

ion 20 upon a shaft 22 having its bearings in the plates 6 and 8, the shaft 22 also having rigidly attached thereto a gear 24 meshing with a pinion 26 upon another shaft 28 having its bearings in the plates 6 and 8, the last mentioned shaft having rigidly attached thereto a ratchet wheel 30 adapted to be engaged by a spring-pressed pawl 32 attached to a gear wheel 34 free to turn on the shaft 28. The gear wheel 34 meshes with a pinion 36 upon a shaft 38 having its bearings in the plates 6 and 8. The shaft 38 also has rigidly attached thereto an escapement wheel 40 with which cooperate escapement pallets 42 and 44 connected together in the usual manner and oscillating upon a short shaft 46 having one of its bearings in the plate 6 and its other bearing in a bracket 48 attached to the inner face of the plate 6. A suitable fan plate 50 (see Fig. 6) attached to the escapement pallets controls the rate of oscillation of the escapement pallets and thus the speed of the make-and-break train.

The make-and-break or code wheel 52 is shown in Fig. 1 attached to the front end of the shaft 28 which extends through the bearing plate 6, the make-and-break wheel 52 being rigidly attached to the shaft 28 in any suitable manner, as by the set screw 54, which permits the removal of the wheel and the substitution of another wheel having thereon a different code.

The shaft 16 associated with the spring 18 is sufficiently long so that its end 56, which is squared to receive a winding key, extends to the outside of the cover 4 of the box.

The train of mechanism which operates the make-and-break or code wheel 52 is normally held against operation by tripping mechanism now to be described. This tripping mechanism comprises a detent or dog 58 pivoted upon the shaft 22 and having one end shaped to engage a pin 60 on the gear wheel 34 to hold this wheel against its tendency to turn in the direction of the arrow in Figs. 8 and 9 under the action of the driving spring 18, the segment gear 12, pinion 20, gear 24, (see Fig. 3) and the pinion 26 on the shaft 28, to which the ratchet wheel 30 engaged by the pawl 32 on said gear 34 is rigidly attached. At its other end the detent or dog 58 carries a pin 62 which engages the shoulder 64 of an opening in a lever 66 fulcrumed at 68 on the front face of the plate 6. The opening in the lever 66 has an enlargement 70 below the shoulder 64 into which the pin 62 on the detent 58 may drop to cause the lower end of the detent 58 to move up out of engagement with the pin 60 on the gear 34. A spring 72 connected at one end to a pin 74 on the detent 58, and at its other end to a pin 76 on the lever 66, tends normally to hold the pin 62 on the detent against the shoulder 64 on

the lever, and to cause said detent to swing as far as permitted by the enlargement 70 when the lever 66 is rocked about its bearing 68 sufficiently to move the shoulder 64 out of engagement with the pin 62. 70

The last mentioned movement of the lever 66 is preferably effected automatically through the trip magnet and its associated armature now to be described. The trip magnet 78 is supported by a bracket 80 attached to the rear wall of the box, and the armature 82 of this magnet, as shown in Figs. 2 and 10, is preferably carried upon a lever or bar 84 having an anti-friction bearing comprising a shaft 86 rigidly connected to said bar or lever 84, the shaft 86 having hardened cones 88 at its end to enter correspondingly hardened bearings, one of which, shown at 90, (see Fig. 2) is preferably adjustable. 80

The lever or bar 84 at its end remote from the bearing carries a pin 92 which is received in a slot 94 in the lever 66, this slot being so located that the movement of the bar or lever 84 with the armature 82 toward and away from the magnet 78 effects the rocking of the lever 66 about its fulcrum 68, thus effecting the tripping and permitting the re-setting of the box. 90

An important feature of the invention is 95 the provision of means for insuring the movement of the armature 82 away from the magnet 78 when the current in the circuit is reduced below operating level so that the box may be reset. As hereinabove suggested, 100 the box is preferably supervised by a closed circuit maintained below operating level, and to overcome the residual magnetism in the magnet and any tendency of the armature to stick due to corrosion, adhesion, 105 atmospheric pressure or other causes, the armature is preferably provided with a spring 96 operating between the armature and the magnet. As shown in Figs. 1 and 10, this spring 96 is preferably located in 110 a recess 98 in the contact face of the armature in such manner that when the armature is attracted to the magnet by a proper operating current, the spring 96 will be bent down until it is received in the recess 98, 115 thus permitting the contact face of the armature 82 to be brought into actual contact with the cooperating face of the magnet 78. When, however, the current through the magnet 78 is reduced to below its operating level to its supervising level, the spring 96 will act to break the contact between the face of the armature 82 and the cooperating face of the magnet 78, thus 120 permitting the armature with its associated lever 84 to move away from the magnet 78 and permit the re-setting of the box. 125

The re-setting of the box is preferably effected automatically near the end of the movement of the segment gear 12 toward the 130

run-down position of the box. The segment gear 12 carries a pin 100 projecting from its front side, as shown in Fig. 2 of the drawings this pin projecting forwardly 5 sufficiently so that it will engage the curved under face of the detent 58 as the segment gear 12 moves toward its run-down position, and swing the detent sufficiently so that its pin 62 will be in position to be engaged 10 by the shoulder 64, and its lower end will be in position to be engaged by the pin 60 on the gear wheel 34. As above stated, this engagement by the pin 100 takes place toward the end of the movement of the segment gear 12 toward its run-down position. 15 To insure the dropping of the lever 84 by the reduction of the current through the magnet 78 below its operating level so that the box will be automatically reset at the end of the operation thereof, provision is 20 made for the breaking of the circuit through the magnet 78 as the segment gear 12 approaches its run-down position, provision being also made for giving a run-down signal at this time. The illustrated means for 25 effecting the breaking of the circuit through the magnet 78 comprises a roll or stud 102 (see Fig. 1) carried upon the front face of the segment gear 12 in such position that as the gear 12 approaches its run-down position this roll or stud 102 will engage the spring member 104 of a circuit-breaking switch and separate the contact members 106 and 108, this switch being in the circuit 30 through the magnet 78. Separation of these members not only permits the dropping of the armature 82 and with it the lever 84, thus restoring the lever 66 to its retaining position with respect to the detent 58, but the breaking of the circuit also gives a 35 trouble alarm by closing a trouble circuit hereinafter to be described.

The make-and-break or code wheel 52 is shown in Fig. 1 in its normal position of rest in which the switch arm 110 of the make-and-break mechanism rests upon a part of the code wheel sufficiently high to maintain the contacts 112 and 114 in engagement, the contact 114 being carried by a 45 second spring arm 116 which on its upper face carries another contact 118 in engagement with the contact 120 on the arm 122 when the spring arm 110 is resting on the part 124 of the code wheel 52. The depressions between the teeth 126 of the code 50 wheel are sufficiently low so that when the spring switch arm 110 drops into one of these depressions not only is the circuit 55 broken by the separation of the contact members 112, 114, but a second circuit is also broken by the separation of the contact members 118, 120.

In addition to the automatic make-and-break mechanism just described, the box is 60 also preferably provided with hand operated

switches by which the operation of the box may be tested and by which other signals than the code signals may be sent. In the illustrated construction, a spring switch arm 128 is shown as provided with two contacts 70 130 and 132, the contact 130 being normally in engagement with a contact 134 on a spring arm or conductor 136, and the contact 132 being adapted to be moved into engagement with the contact 138 on an arm 140. 75

The means for moving the switch arm 128 to effect either the separation of the contacts 130 and 134 to break the circuit in which they are included, or the engagement of the contact members 132 and 138 to complete a circuit of which they form a part, comprises a lever 142 having a rectangular slot 144 into which the free end of the switch arm 128 extends, this lever 142, as shown in Figs. 2 and 3 of the drawings, being attached to a short shaft 146 having its bearings in a plate 148 upon the front face of the plate 6, and in a bracket 150 attached to the plate 148, the shaft 146 extending through the cover plate 4 of the casing and 80 being provided with a squared outer end 152 to receive a key by which the swinging of the lever 142 against the tendency of the spring 154 to hold it in the position shown in Fig. 1 may be effected. It will be seen 85 that the lever 142 may be swung in either direction about its axis, and that when swung in a clockwise direction it brings the contact 132 into engagement with the contact 138 and closes the circuit of which these 90 form a part, and when swung in a counter-clockwise direction, Fig. 1, it effects the separation of the contacts 130 and 134 and breaks the normally closed circuit in which they are included. 95

The box is also preferably provided with a resistance element which may be in the form of a coil 156, the illustrated coil being shown in detail in the sectional view in Fig. 7 of the drawings. It will be noted 100 that two leads 158 and 160 come into the same end of the coil, these leads being connected respectively to conductors 162 and 164 shown in plan view in Fig. 1, and one of the leads 160 being also connected to one 105 end of the resistance winding of the coil, the other end of this winding being connected to a lead 161 at the other end of the coil. The conductors 162 and 164 are separated 110 but have opposed recesses so arranged that a short-circuiting spring key 166 may be inserted into the hollow center 168 of the coil in such manner that it engages the two conductors and short-circuits the coil, thus cutting the resistance out of the circuit in 115 which it would normally be included when the key is not in the position shown in Fig. 7. 120

Having reference now to Fig. 12 of the drawings, it will be noted that the trip mag- 125 130

net 78 is in a circuit comprising a wire 170 coming in upon the control board 172 at 174, and that the other wire 176 from the magnet 78 comes in from an outside circuit 5 which may include a release box 178, one side 180 of a two-wire circuit coming in upon the control board at 182, a trouble relay magnet 184 upon the control board, and the other side 186 of the two-wire circuit 10 leaving the control board at 188 and returning to the board through the switch 108 and 106 of the transmitter box and coming back upon the board at 190.

Current for supervising and operating the 15 mechanism upon the control board and the mechanism in the transmitter box may be supplied from the city mains, or a battery, or other suitable local source, and in the illustrated control board is shown as brought 20 upon the board at the positive terminal 192 and as leaving the board at the negative terminal 194, the two-wire circuit just described being connected to the positive terminal 192 through the wire 196 and the fuse 198 and 25 being connected to the negative terminal through the wire 200, the switch 202 normally short-circuiting the ammeter 204, and through the balancing resistance 206 and the fuse 208.

30 The trouble relay magnet 184 at the end of the two-wire circuit just described constitutes resistance sufficient to cut down the current brought in upon the control board 172 below the level at which it will operate 35 the release box 178 and the trip magnet 78. This resistance may be short-circuited out of the circuit in any suitable manner as, for example, by means of fusible thermostats 210 of the type shown and described in the 40 Letters Patent of John H. Derby and Ernest Seymour Clayton, #1,274,248, dated July 30, 1918, or by means of a hand-operated short-circuiting switch in the transmitter box, this switch comprising an upper spring 45 switch arm 212 carrying a contact 214, and a lower switch arm 216 carrying a contact 218.

As shown in Figs. 1, 2 and 11, the switch arm 212 has upon its upper side a small cam 50 220 adapted to be engaged by a stud or roll 222 carried upon an upwardly extending arm 224 of a lever fulcrumed at 226 on the inner face of the cover 4 of the box (see Fig. 11). A pin 228 on the lever 224 projects through a slot 230 in the cover plate 4 and carries upon the outside of said box 55 a knob or handle 232 by which the pin 228 may be moved up and down in the slot 230, thus rocking the lever 224 and causing the 60 stud or roll 222 to press down upon the cam 220 and force the contact 214 into engagement with the contact 218, thus short-circuiting the trouble relay 184 and causing an increased flow of current through the circuit, 65 including the release box 178 and the mag-

net 78, this increase of current being sufficient to operate the release box and trip the automatic transmitter mechanism.

Any break in the circuit just described 70 would cause the trouble relay 184 to drop its armature 234 and close the circuit through a trouble gong hereinafter to be described. As hereinabove described, the circuit is broken by the separation of the contacts 106, 108 when the transmitter box runs down, as 75 shown in Fig. 1 of the drawings, thus giving a trouble alarm.

The circuit for the make-and-break signal transmitting mechanism shown in Fig. 12 80 comprises a wire 236 leading from the spring switch member 112 through the switch arm 128, through the contacts 130 and 134, switch member 136, wire 238, trouble relay magnet 240, wire 242, gong 244, which may be located in the office or 85 engine room, register 246, also similarly located, wire 248, wire 250, balancing resistance 206, fuse 208 to the negative terminal 194 on the board, the other side of the circuit comprising the switch member 116, wire 252 and wire 254, balancing resistance 256, 90 fuse 198 to the positive terminal 192.

The second make-and-break circuit is a 95 normally open circuit adapted to be closed by the short-circuiting key 166 associated with the resistance coil 156, this circuit comprising the switch member 122, wire 158 leading to one of the contact members 162, 164 of the resistance element, and the wire 160 leading from the other contact member 100 of said resistance element to a double-ended relay magnet 260 from which a wire 264 leads to a trip magnet 266 of an outside transmitter box of the city alarm system, the negative side of the circuit being completed by wire 268 to wire 250, back to the 105 negative terminal 194, the positive side of this circuit including the switch member 116, and the wires 252 and 254 to the positive 110 terminal.

The resistance 156 is connected between the wires 160 and 252 so that a supervising current flows through this resistance 156 which supervises the circuit including the relays 260 and 266, one end of the relay 260 115 being associated with a trouble circuit. When the key 166 is inserted between the contact members 162 and 164, the resistance 156 is short-circuited and sufficient current is permitted to flow through the relay 260 120 to draw down the armature 270 and close the circuit which includes the wire 254 from the positive terminal 192, the wire 272, balancing resistance 274, floor gongs 276, 278, 280 and wire 282, back to wire 250 and the 125 negative terminal 194. Thus when the resistance 156 is cut out of the transmitter box, a coded signal will be sent to each floor upon the manual tripping of the transmitter, giving a local alarm for arousing the occupants 130

of the building. The increased flow of current will also energize the magnet 266 sufficiently to trip the code transmitting wheel 284 for sending an alarm to the fire station.

- 5 The normally open code signal circuit which includes the floor alarms is supervised by a current passing through the trouble relay magnet 286, the positive side of this circuit coming to the relay magnet 286 through the wires 254, 252, the resistance 156, and the wires 160 and 288, and the negative side of this circuit coming to the relay 286 through the wires 290, 272, resistance 274, single stroke gongs 276, 278, 280 10 and wires 282 and 250.

- 15 In order to operate the transmitter box, that is, particularly the train of mechanism including the code wheel, without transmitting a code signal, as for example 20 when it is desired to test the mechanism, means are preferably provided for short-circuiting the code signal transmitting circuit, the illustrated means comprising the switch arm 128, the contacts 132 and 138 and 25 the switch member 140, the contact 132 being adapted to be moved into circuit-closing relation to the contact 138 through the turning of the lever 142 in a clockwise direction. As shown in Fig. 12 of the drawings, this short-circuits the code transmitting switch members 116 and 110 through the switch member 140 and the wire 292 leading back to the wire 161. Turning of the code wheel 52 will, therefore, have no 30 effect upon the circuit which is now completed through the switch members 140, 128 and 136.

- 35 The trouble relays and trouble signal circuits are shown diagrammatically in Fig. 40 13 of the drawings, there being four of these trouble relays, 184, 240, 260 and 286, each normally in a closed circuit, the respective circuits supervised by these four relays having been hereinabove described. 45 Each of the relays has associated therewith an armature normally held by the current passing through the closed circuit in which the relay is included out of circuit-closing relation to a co-operating contact member 50 in a circuit which includes the trouble alarm 294. In the case of the relays 184, 240 and 286, the respective armatures 234, 296 and 298 are arranged to gravitate into circuit-closing relation to the respective co-operating contacts 300, 302, 304, while in the case of the armature 306 of the horizontal relay magnet 260 a spring 308 is provided which tends to move this armature into engagement with the co-operating contact member 310. From an inspection of the wiring diagram in Fig. 13, it will be apparent that whenever a circuit including any of the relays is broken, the movement of the associated armature thus released will 60 complete a circuit through the trouble alarm

294 and the local trouble circuit battery 312.

In order that the train of mechanism operating the code wheel may be released when there is no current passing through the 70 transmitter box or through the circuit which includes the magnet 78, the lever 224 (see Figs. 2 and 11) is preferably provided with an arm 314 which extends beneath the lever 84 so that when the knob or handle 232 is 75 pushed downward the upward movement of the arm 314 of the lever 224 will effect the movement of the lever 84 and the associated armature 82 toward the magnet 78, thus tripping the train of operating mechanism 80 for the code wheel in the same manner that it is tripped automatically by the energization of the magnet 78.

85 From the foregoing description, the operation of the transmitter box will readily be understood. If one of the thermostatic circuit controllers 210 be caused to short circuit the trouble relay magnet 184, which is of sufficient resistance to maintain the current in the circuit including these thermostatic elements at a supervising level and below operating level, the increased current flow caused by the short-circuiting of the relay magnet 184 will operate the release box or boxes 178. Such release boxes are 90 usually employed to effect the closing of fire doors, dip tank covers and the stopping of blowers and other machinery that might increase the fire hazard. The increased current flow will also energize the 95 magnet 78 sufficiently to cause it to draw the armature 82 and with it the connected lever 84, thus moving the shoulder 64 on the lever 66 out of engagement with the pin 62 on the 100 detent 58, whereupon the spring 72 causes the detent 58 to rock until its end is out of engagement with the pin 60 on the gear wheel 34, thereby releasing the train of 105 operating mechanisms for the code wheel 52.

110 The spring 18 being wound up and the segment gear 12 being in the position shown in Fig. 8 of the drawings, the release of the operating mechanism by the movement of the detent 58 out of engagement with the pin 60 permits the segment gear 12 to be 115 moved upward in the direction of the arrow, Figs. 8 and 9, thereby, through the train of pinions and gears, driving the code wheel 52 and causing it to transmit a coded signal to the local gong 244 and to the register 246, which may be in the engine room or in the office of the building, it being obvious, of course, that signals may be provided in both places if desired. This coded signal is sent through the circuit, including the switch member 110, wire 236, switch member 128, switch member 136, wire 238, the trouble relay 240, wire 242, gong 244, register 246, wire 248, wire 250, negative terminal 194, positive terminal 192, wire 254, 120 125 wire 256, switch member 130, switch member 132, wire 258, switch member 134, wire 260, switch member 138, wire 262, switch member 140, wire 264, switch member 142, wire 266, switch member 144, wire 268, switch member 146, wire 270, switch member 148, wire 272, switch member 150, wire 274, switch member 152, wire 276, switch member 154, wire 278, switch member 156, wire 280, switch member 158, wire 282, switch member 160, wire 284, switch member 162, wire 286, switch member 164, wire 288, switch member 166, wire 290, switch member 168, wire 292, switch member 170, wire 294, switch member 172, wire 296, switch member 174, wire 298, switch member 176, wire 300, switch member 178, wire 302, switch member 180, wire 304, switch member 182, wire 306, switch member 184, wire 308, switch member 186, wire 310, switch member 188, wire 312, switch member 190, wire 314, switch member 192, wire 316, switch member 194, wire 318, switch member 196, wire 320, switch member 198, wire 322, switch member 200, wire 324, switch member 202, wire 326, switch member 204, wire 328, switch member 206, wire 330, switch member 208, wire 332, switch member 210, wire 334, switch member 212, wire 336, switch member 214, wire 338, switch member 216, wire 340, switch member 218, wire 342, switch member 220, wire 344, switch member 222, wire 346, switch member 224, wire 348, switch member 226, wire 350, switch member 228, wire 352, switch member 230, wire 354, switch member 232, wire 356, switch member 234, wire 358, switch member 236, wire 360, switch member 238, wire 362, switch member 240, wire 364, switch member 242, wire 366, switch member 244, wire 368, switch member 246, wire 370, switch member wire 252, and switch member 116—see Fig. 12 of the drawings. Because of the interposition of the resistance 156, sufficient current will not flow through the circuit which 5 includes the relay 260 and the trip magnet or relay 266 to draw up their armatures and thus no alarm will be sent to fire headquarters or to the floors of the building.

If now it is desired to make the alarm 10 general and give warning to the occupants of the building and at the same time send an alarm to fire headquarters, the plug or key 166 is inserted between the contact members 162 and 164 to short circuit the resistance 156, whereupon the increased flow of current through the circuit, including the switch members 116, 122, the wires 158, 160, the relay magnet 260, wire 264, the trip magnet 266, wire 268, wire 250, negative terminal 194, positive terminal 192, wires 254, 252 and 161, will cause a coded signal to be sent to the building floors by the drawing down of the armature 270, closing the circuit through the single stroke gongs 276, 278, 280, 25 and will cause the tripping of the outside signal box containing the code wheel 284 for transmitting an alarm to fire headquarters, said box being reset either before or after the key 166 is inserted and again 30 tripped, this tripping being effected by hand. The resetting of the box is effected by winding the spring 18 through a key upon the shaft 16 as hereinabove described.

As the transmitter box runs down and 35 the segment gear 12 approaches the upper limit of its movement, the stud or roll 102 on this segment gear engages the switch member 104 and separates the contacts 106, 108, thus breaking the circuit including the 40 trouble relay magnet 184, thereby permitting its armature 234 to drop into engagement with the cooperating contact member 300 whereupon a trouble signal is given by the trouble alarm bell 294.

Should the watchman or other person intending to operate the box desire to send an alarm to fire headquarters without operating the local alarm, this can be done by simply plugging in the key 166 to short circuit the resistance 156 when the box is at rest. This will result in the bells 276, 278, 280 being given a single stroke but not a 50 coded alarm and in the energization of the tripping magnet 266. If, after doing this, 55 he still desires to send a coded alarm throughout the building, he can then pull down on the knob 232, thus both short-circuiting the resistance 184 in the circuit which includes the trip magnet 78 and also 60 positively lifting the lever 84 to effect the positive tripping of the train of mechanism which drives the code wheel 52. The circuit making-and-breaking action of the code wheel 52 will then cause a coded signal to 65 be sent throughout the building. This

short-circuiting action will also effect the operation of the release box 178.

From the foregoing description it will be seen that the box is arranged to be operated both automatically and manually, and that 70 it is also arranged either automatically or manually to give a local alarm only, an alarm to fire headquarters only, or both a local alarm and an alarm to fire headquarters. It will also be seen that all of the circuits, including the normally open circuit to the floor alarms, is under supervision and that whenever a break occurs in any of these circuits a trouble alarm is given.

From an inspection of Fig. 1 of the drawings, it will be noted that when the armature 82 and its attached lever 84 is in retaining position, the spring 96 carried by the armature is not under tension and that it is not brought under tension until the armature has moved sufficiently toward the magnet, when the magnet has been energized, to bring it into the field of strong magnetic action. At the same time, the interposition of the spring 96 between the armature and the magnet serves a further purpose in that it makes the transmitter mechanism substantially jar-proof. In other words, the spring prevents a sufficient upward movement of the armature 82 and lever 84 when the box is jarred to permit the tripping of the mechanism.

This is a particularly important feature of the present invention as it prevents the 100 tripping of the transmitter and the sending of a false alarm due to vibration or jarring of the transmitter. The accidental tripping of the transmitter in this manner has been a common occurrence in transmitters heretofore produced.

What I claim as new is:

1. In an electric signal transmitting system, a transmitter box and a local signal circuit through which said box is arranged to transmit local signals, a second transmitter box and a circuit through which it transmits signals to headquarters, connections between the first box and the second transmitter box resistance in the connections to said second transmitter, and means at said first transmitter for cutting out said resistance when it is desired to automatically transmit a signal to headquarters.

2. In an electric signal transmitting system, a transmitter box having therein make-and-break signal transmitting means normally in closed circuit condition, a trouble relay in said circuit for indicating a break in said circuit when said transmitting means is not operating, a second circuit including a shunt through said transmitter box controlled from said transmitter mechanism for governing the sending of signals to headquarters, said second circuit being also normally closed except through said shunt, re-

sistance in said second circuit arranged to be short-circuited by closing said shunt and a trouble relay in said second circuit for indicating a break in said circuit.

- 5 3. In an electric signaling system, the combination with a transmitting device comprising a make-and-break code signal transmitting wheel, a normally open relay-controlled signal circuit associated with said 10 code wheel, a relay circuit also associated with said code wheel and having resistance therein normally maintaining the current in said circuit below relay operating level, means at said transmitting device for short-circuiting said resistance, and means for 15 bridging the normally open signal circuit at said relay, said means including a trouble relay wound to provide a supervising current for said signal circuit below the signal 20 operating level.

4. In an electric signal transmitting system, the combination with a code signal transmitting device, including a code wheel and make-and-break switch mechanism, of 25 separate normally closed circuits controlled by said make-and-break switch mechanism, one of said circuits including signaling means directly in circuit with said switch mechanism, and another circuit including a 30 relay, resistance in said relay circuit maintaining the current in said circuit below relay operating level, and means at said transmitting device for short-circuiting said resistance to operate said relay.

- 35 5. In an electric signaling system, a transmitter box adapted to control the transmission both of local signals and of signals to fire headquarters, said box having therein signal transmitting means includ-

40 ing a code wheel and make-and-break switch

mechanism operated by said code wheel, separate normally closed circuits controlled by said make-and-break switch mechanism, one of said circuits including signaling means directly in circuit with said switch 45 mechanism, another circuit including means for actuating a fire headquarters transmitter, resistance in said last-mentioned circuit maintaining the current therein below the operating level of said actuating means, and 50 means in said transmitter box for short-circuiting said resistance to raise the current in said last-mentioned circuit to operating level.

6. In an electric signal transmitting system, 55 the combination with a code signal transmitting device including a code wheel and make-and-break switch mechanism, of a plurality of normally closed circuits controlled by said make-and-break switch 60 mechanism, one of said circuits including signaling means directly in circuit with said switch mechanism and operable by the normal current flowing through said circuit, another circuit including a relay and also 65 means for actuating a fire department transmitter, resistance in said last-mentioned circuit normally maintaining the current flow therein below operating level for said relay and for said actuating means, a local 70 floor gong circuit controlled from said relay, and means at said transmitting device for short-circuiting said resistance to cause the operation of said local gongs through said code wheel and the transmission of a 75 signal to fire headquarters.

Signed at New York city, N. Y., this 15th day of June 1922.

JOHN H. DERBY.
